SCRAPER WITH SCOOP LIFT MECHANISM

Charles Le Bleu, Los Angeles, Calif., assignor to
Davenport Manufacturing Company, Los Angeles, Calif., a corporation of California

Application April 8, 1932, Serial No. 603,959

2 Claims. (Cl. 37—129)

This invention relates to a scraper adapted to be drawn across the surface of the ground and provided with a scoop or bowl and novel means for controlling the position of the bowl. Wheeled scrapers have heretofore been provided having scoops which can be set at various angles for loading, carrying and dumping. Such bowls have been commonly supported on a pivotal axis about which the scoop may be rocked. This axis is usually fixed with respect to the frame and the scoop is made to assume loading, carrying and dumping positions by turning it about its pivotal axis. The clearance of the bottom of the bowl when carrying a load and the angle when loading are dependent on the height of the pivotal axis above the ground. It is well known that the greater the angle at which the bottom and blade are presented to the ground in loading, the greater will be the power required to force the dirt back into the scoop. If in the conventional type of scraper as above described, a small angle is provided it will be at the expense of clearance in carrying position. It is advantageous to have the blade and bottom capable of being disposed in a substantially flat position in loading and at a comparatively high level in carrying. With a high lift off the ground, the scoop may clear an obstruction without digging into the latter and with a flat angle for loading, a minimum of power is required.

The primary object of this invention is to provide a scraper having a bowl so mounted and controlled that a high lift in carrying may be obtained and a flat angle of the bottom and blade in loading. Another object of this invention is the provision of a scraper wherein the rear end of the bowl may be moved toward the ground as the front end is moved away from the ground so as to retain dirt, and when the limit of the rear end movement has been reached, the bowl as a whole moves upwardly. In addition to the broader objects of this invention, there are other more specific objects which may be obtained by a scraper having any or all of the following features: A scraper having a bowl the level of whose pivotal suspension from the scraper frame may be selectively adjusted; a bowl control mechanism whereby the angle of the cutting edge presented to the ground may be altered at will; a scraper in which the bowl may be bodily lifted; and hydraulic means for bodily lifting the bowl and hydraulic means for tilting the bowl.

These objects together with other objects which will be apparent from the subjoined description are obtained by means of the embodiment of my

invention illustrated in the accompanying drawings, in which:—

Fig. 1 is a side elevation of a wheeled scraper with bowl in carrying position and a fragment of the tractor; Fig. 2 is a plan view of a lateral fragment; Figs. 3 and 4 are side elevations showing the bowl in loading and dumping positions respectively; Fig. 5 is a side elevation partly in section on an enlarged scale of the upper hydraulic cylinder for controlling the elevation of the tilting axis; Fig. 6 is a section as seen on the line 6—6 of Fig. 5; Fig. 7 is a section as seen on the line 7—7 of Fig. 1, on an enlarged scale showing the valve mechanism for controlling the hydraulic cylinder; Figs. 8, 9 and 10 are sections on an enlarged scale as seen on the lines correspondingly numbered in Fig. 7; Figs. 11 and 12 are sections as seen on the lines correspondingly numbered in Fig. 9; Fig. 13 is a perspective view of one of the valve plugs.

Referring more particularly to the drawings and especially to Fig. 1, a supporting frame A carries a movable scoop B. The frame is supported upon rear wheels C and at the front by a coupling to a tractor D.

The frame comprises side bars 15. Depending from the side bars are bracket arms 16. Pivotally secured to the bracket arms are swing links 17. The scoop B comprises side walls 18, and a back 19. A removable bottom 20 is secured to the scoop by means of bolts 21. There is also a removable digging blade 22 similarly secured to the bottom of the scoop. A blade, not shown, may be attached to the rear wall of the scoop when the bottom is removed and the machine operated as a leveller. Swing links 17 are pivotally connected to the side walls 18 of the scoop and support the latter at the front about a pivotal axis 23. This is a turning axis for tilting the scoop. A shaft 24 is journaled in bearings mounted on the side bars and is provided at its ends with crank arms 25. The crank arms 25 are secured by rocker bars 26 to the swing links 17 intermediate the ends of the latter. The construction is such that when the shaft 24 is turned the elevation of the turning axis 23 of the scoop is raised or lowered. At the center of shaft 24 is a crank arm 27 which is pivotally secured to the outer end of a piston rod 28. The piston rod is moved by a piston within a hydraulic cylinder 29 which is pivotally secured at 30 to a bracket supported by a frame A. The hydraulic cylinder is double acting and with its piston constitutes a thrust member which is extensible.

It controls the swinging of links 17 and thereby the level of the turning axis of the scoop.

Secured to the scoop at its rear is a bracket 31 to which a piston rod 32 is pivotally secured. The piston rod is operated from the piston in a double acting cylinder 33. The hanger comprising cylinder 33 and piston 32 may maintain the rear of the scoop in position such that the bottom is substantially horizontal. It is obvious that the scoop may be tilted by contracting or expanding the thrust hanger. Referring to Fig. 3, the scoop is shown in loading position. The thrust member comprising cylinder 29 and piston 28 has been expanded to lower the turning axis 23. The scoop may be tilted from the position shown in Fig. 1 by raising its rear, the height of the scoop above the ground being controlled by the position of the turning axis. It will be noted from Fig. 3 that the scoop may have its bottom disposed in a substantially flat position so that a minimum of force will be required to load. Any digging angle may be obtained by raising and lowering the rear end of the scoop through the thrust hanger and any depth of cut by raising or lowering the turning axis. In Fig. 4 the scoop is shown in dumping position. In practice with the conventional types of scrapers a clearance of only about two inches above the ground is obtained. This is entirely inadequate for work because in many instances such as building up of bridge approaches, building levees, raised road beds, etc., there will be a mound of earth such as the rim of an embankment between the tractor and scoop and, unless the scoop can be left high enough to clear this obstruction, it will dig into the latter as the tractor advances. With my improved scraper the scoop can be set flat on the ground or at any desired angle for taking the load and may be lifted high off the ground for transporting the load. This height may be from 16 to 24 inches in practical scrapers.

The hydraulic mechanism for operation of the scoop comprises the cylinder 33 having a piston 35 reciprocatingly mounted therein. The head 36 of the cylinder has an extension chamber therein and a pipe 37 which is connected by suitable fittings to a flow line 38. A branch 39 connected to the cylinder 33 has a valve casing 40 with a check valve enabling outward flow therethrough from the cylinder. At the other end of the cylinder 33 is a pipe 41 connected into the head and to a flow line 42. A branch 43 connects line 42 to the cylinder. Fluid under pressure is supplied to one end of cylinder 33 through one flow line and exhausted from the other end through the other flow line. Control of the flow is effected by a valve mechanism hereafter described, pressure fluid being supplied by a continuously operating pump in the nature of a fluid transmission system with a storage tank on the intake side of the pump. Provision is made in the valve mechanism to by-pass fluid in positions wherein piston 35 is intermediate its extreme end positions. If the piston 35 is at its extreme left end position, it will have uncovered the port opening 39a of the branch 39. Pressure fluid to attain the left end position of piston 35 will have entered the right hand end of the piston by way of line 42. It will be apparent that pressure fluid may continue to flow through the cylinder from line 42 and by way of branch 39 and line 38 return to the pump by way of the storage tank, thereby preventing stalling of the pump. If the flow of pressure fluid is reversed 75 to move the piston 35 to the right, fluid will

enter the left hand end of cylinder 33 by way of line 38 and branch 37, the valve 40 preventing entrance of pressure fluid to the other side of the piston. At the right hand position of the piston, port 43a will be uncovered and fluid may flow through the cylinder from line 38 by way of branch 43 and return to the pump through line 42. This prevents stalling of the pump. As the weight of the scoop tends to draw the piston 35 to the left, no check valve in branch 43 is necessary to start the piston in its travel. Cylinder 29 has an extension head 44 similar to head 36 on cylinder 33 and a flow line 45 is connected thereto. This flow line has no branch. At the opposite end of cylinder 29 a flow line 46 is connected thereto having branches 47 and 48 entering the cylinder. The operation is similar to that of cylinder 33. However, since the scoop B in its lowest digging or loading position would engage the ground at its nose, the piston would be prevented from reaching the extreme left hand position and no by-pass in the cylinder is necessary at the left end.

Referring to Figs. 7 to 13, a valve cylinder 49 has flow lines 38 and 42 connected to its sides 25 adjacent one end angularly spaced 90° to one another. Flow lines 45 and 46 are connected to the sides of cylinder 49 at the opposite ends at angularly spaced distances of 90° and angularly intermediate the connections of flow lines 38 and 42. Rotatably mounted on cylinder 49 are valve plugs 50a and 50b of similar construction, one being shown in Fig. 13 and marked with reference numerals having no alphabetical affix. The plugs have bosses 51a and 51b extending from the ends 35 and abutting each other as shown in Figs. 8 and 11. These plugs are independently rotatable and the construction provides an annular channel 52 in the casing. Intermediate the ends of the plugs are channels or ports 53a and 53b extending over about 90° of the surface of the plugs and opening to the diametrically opposite sides by ports 54a and 54b. Ports 55a, 55b, 56a, and 56b open through the periphery of the plugs at ports 90° to ports 54a and 52b and extend through 45 the inner faces of the plugs to channel 52. From the ends of the plugs operating stems 57a and 57b extend passing through the heads in valve cylinder 49. In the valve casing 49 extending longitudinally thereof is a passage 58 having ports 50 opening through to the bore of the casing in circumferential alignment with ports 53a and 54a and ports 53b and 54b. Diametrically opposite to passage 58 is a passage 59 opening at its ends to the bore of the casing in circumferential alignment with channel 52 and ports 53b and 54b. The casing 49 has a pump discharge line 60 opening to the bore of the casing through an inlet port 60a in alignment with ports 53a and 54a. A pump intake line 61 is connected to the casing 60 through an outlet port 61a in line with channel 52.

Assuming, the valve plugs are in the position shown in Fig. 8, pressure fluid from the pump may pass by way of pump discharge line 60, ports 65 60a, 53a, 54a, channel 58, ports 53b, 54b, channel 59, chamber 52 and port 61a to the pump intake line 61. The ports 38a, 42a, 45a and 46a leading from flow lines 38, 42, 45 and 46 to the cylinders 33 and 29 are closed. The pistons in cylinders 33 and 29 are then locked. Suppose it is desired to move piston 35 in cylinder 33 to the right. Plug 50b is turned to position port 54b in registry with port 38a. Fluid enters the casing from pump discharge line 60 passes through the 75

ports in plug 50a to channel 58, by way of ports 53b, 54b and 38a to flow line 38. In this position, port 56b registers with port 42a. Line 38 is now in communication with line 60 by way of the ports in plug 50a and channel 58 and pressure fluid is supplied to the left hand end of cylinder 33. The intake line 61 of the pump is connected by way of chamber 52, ports 56b and 42a to flow line 42 leading to the right hand end of cylinder 33. When piston 35 has reached its desired position, plug 50b is turned to neutral or locking position as shown in Fig. 10. If the plug is maintained in the position for moving piston 35 until the latter reaches the right hand end of cylinder 33, fluid may continue to flow from the discharge line 60 to the intake line 61 of the pump through port 43a and flow line 42 so that the pump is not stalled. To move the piston 35 to the left, plug 50b is turned to register port 54b with port 42a and port 55b with port 38a. The flow is then reversed. Suppose the plugs are in locked position and it is desired to operate cylinder 29 and plug 50a is turned to register port 54a with port 45a. Fluid from the pump discharge line 60 passes through ports 60a, 53a, 54a, and 45a to flow line 45 and thence to the left hand end of cylinder 29. In this position of plug 50a, port 56a registers with port 46a and fluid may pass from the right hand end of cylinder 29 by way of flow line 46, ports 46a, 56a, chamber 52 to pump intake line 61. By registering port 54a with port 46a, and port 55a with port 45a, fluid flows from the pump in reverse direction. Obviously either cylinder 29 or 33 or both may be operated as desired without stalling the pump.

For convenient manipulation of the plugs, a crank arm 62a is connected to shaft 57a and a crank arm 62b to shaft 57b. These crank arms are operated by link rods and bell cranks from 40 crank handles 63a and 63b. A supply tank 64 is interposed between the casing 49 and pump intake, the pump being indicated by 65 in Fig. 7.

In order to balance pressures on the peripheries of the plugs, tubes 66 are suitably connected to 45 channels 67 and recesses. As these form no part of the present invention they are not described in detail.

When the bowl is in the position shown in Fig. 3, the valve mechanism may be operated to admit pressure fluid to the right hand end of cylinder 33 and connect the left hand end to discharge. This causes the bowl to be tilted by lowering the rear of the bowl. Without changing the position of the valve plug 50b, the valve plug 50a may be operated to admit pressure fluid to the left hand end of cylinder 29, raising the bowl as a whole. Operation of plug 50a as de-

scribed will shut off the flow of fluid to cylinder 33, but the piston in the latter may move to its outer left hand position creating a partial vacuum behind it

What I claim is:—

1. A dirt moving device comprising a running gear, a frame carried thereby and adapted to be mounted in a substantially horizontal position, pivot brackets on said frame, swing links pivotally connected by their front ends to said 10 brackets and adapted to extend rearwardly and to swing vertically, a scoop disposed between elements of the frame, trunnions carried by the scoop on the opposite sides thereof and adjacent to the entering edge of the scoop whereby the 15 scoop may be given bodily vertical adjustment and may rotate on said trunnions, said trunnions being pivotally supported by rigid mechanical linkage pivoted upon the frame and engaging said swing links adjacent to the trunnions, pneumati- 20 cally operated means for moving said linkage and for positively holding the same in a set position, a thrust hanger structure mounted at its forward end to a fixed pivot disposed forwardly of the scoop and carried by the frame, means pivotally 25 connecting the free end of said thrust hanger structure with the upper rear edge of the scoop, and fluid pressure means embodied in said thrust hanger structure to swing the scoop upon the axis 30 of its trunnions and to positively hold the scoop in a set position.

2. A dirt moving device comprising a running gear, a frame carried thereby, a scoop adapted to be supported by the running gear, a bracket rigidly secured to the frame in advance of the 35 scoop, trunnions carried at the opposite sides of the scoop and adjacent the forward lower edge thereof, swinging links pivoted to the brackets and trunnions, an operating shaft pivotally mounted upon the frame and thereabove, said shaft being disposed at a point intermediate the ends of the swinging links, crank arms pivoted upon the shaft for vertical swinging movement, rocker bars pivotally connected to the free ends of the 40 crank arms and to the swinging links, the last 45 named pivots being disposed slightly in advance of the connection of the swinging links with the trunnions, a rigid bracket carried by the upper rear edge of the scoop, hydraulic jack pivotally connected therewith and pivotally connected to 50 the main frame, a power lever pivotally connected to the shaft of the crank arms, a hydraulic jack connected therewith, and pivotally connected to the main frame, and means separately operating said hydraulic jacks. 55

CHARLES LE BLEU:
